UNITED STATES PATENT OFFICE.

THOMAS J. MCADAMS, OF MARION, ILLINOIS.

BURNER.

1,128,338.

Specification of Letters Patent.

Patented Feb. 16, 1915.

Application filed June 11, 1914. Serial No. 844,579.

To all whom it may concern:

Be it known that I, THOMAS J. MCADAMS, a citizen of the United States, residing at Marion, in the county of Williamson and 5 State of Illinois, have invented new and useful Improvements in Burners, of which the following is a specification.

The invention relates to hydro-carbon burners, and more particularly to the class 10 of fuel vaporizers for use in stoves, furnaces, or the like.

The primary object of the invention is the provision of an apparatus of this character wherein the fuel will be fed to a column 15 for the preheating thereof so that it will become vaporized to produce gas prior to the consumption thereof at the burner, the retort being of novel form, and likewise the burner is of novel form to insure the 20 perfect working thereof and the saving of fuel.

Another object of the invention is the provision of a device of this character wherein the same can be readily mounted within 25 the stove or other heater and is capable of positive control to regulate the flame as well as the supply of fuel thereto.

A further object of the invention is the provision of a device of this character 30 wherein the fuel prior to the lighting thereof is superheated to convert the same into gas to be consumed at the burner, the flame from the burner serving to preheat the retort for vaporizing the fuel.

35 A still further object of the invention is the provision of a device of this character wherein the valve rods for controlling the valves of the burner and the supply thereto are capable of adjustment so that they may 40 be properly positioned for convenient manipulation when the device is placed within a stove or other heater.

A still further object of the invention is the provision of a device of this character 45 which is simple in construction, reliable and efficient in operation, and inexpensive in manufacture.

With these and other objects in view, the invention consists in the construction, combination and arrangement of parts as will be hereinafter fully described, illustrated in the accompanying drawings, and pointed out in the claims hereunto appended.

In the drawings: Figure 1 is a side elevation 50 of a portable stove, showing the device

constructed in accordance with the invention applied. Fig. 2 is an enlarged vertical transverse sectional view through one of the vaporizers, showing the burner in side elevation. Fig. 3 is a fragmentary vertical 60 sectional view through an ordinary coal stove, showing the device applied thereto. Fig. 4 is a sectional view on the line 4-4 of Fig. 2. Fig. 5 is an enlarged fragmentary side elevation of one of the vaporizing 65 heads. Fig. 6 is a fragmentary vertical sectional view through the base of the device, showing one of the extensible valve rods, the same being partly in section.

Similar reference characters indicate 70 corresponding parts throughout the several views in the drawings.

Referring to the drawings in detail, A designates the frame of an ordinary portable stove which supports the device comprising a base 10, the same being mounted in any suitable manner in the frame A and has fixed thereto an elbow 11 in which is tapped the fuel feed pipe 12 at one end thereof, the said pipe 12 being extended outwardly and upwardly above the top of the frame A to a suitable point of elevation, where it is connected with an oil reservoir 13 of any approved type, the pipe being provided with a cut-off valve 14 for controlling the feed of oil from the reservoir to the retort of the burner presently described.

Connected to the other end of the elbow 11 is a tubular preheating column 15 carrying a hollow vaporizing head 16, the same being formed with an open center 17, while within the head 16 concentric to the open center 17 are inner and outer series of baffle plates or partitions 18 and 19, respectively, the partitions 18 extending outwardly 95 radially from the wall of the open center 17 of the head and terminate spaced from the outer wall of the said head, while the plates or partitions 19 extend inwardly from the outer wall of the head and terminate spaced from the wall of the open center 17 thereof

so that the fluid admitted to the head from the column 15 will circulate in a zigzag course through the head, and by reason of the presence of the baffle plates or partitions 100 within the vaporizing head the pressure of gas when produced therein will be retarded to obviate back flow of the oil admitted to the said head from the column 15. Formed between the plates or partitions 18 and 19

105

110

- and concentric to the open center 17 of the head 16 are air passages 20 which open through the top and bottom of the head, the partitions 18 and 19 being vertically arranged within the head, while formed within the column 15 are horizontally disposed baffle plates or partitions 21 which are arranged in spaced relation to each other and are provided with openings 22 disposed in a staggered relation to each other so as to deflect the course of the fluid when rising therein, which is supplied thereto through the feed pipe 12, and these baffle plates or partitions 21 with the openings arranged therein also serve to retard the flow of gas which otherwise would exert pressure upon the oil causing back pressure thereof. Immediately below the lowermost partition or baffle plate 22 in the column 15 is a reticulated valve cage 23, the top of which is closed by the said lowermost partition, and it rises centrally from a partition 24 formed with a valve seat 25 against which normally rests a spherical valve 26 which works within the cage 23, and this valve is adapted to open under the pressure of the fuel supplied from the feed pipe 12, and on the seating of the said valve 26 the supply is automatically cut off, as will be apparent.
- 30 Fixed within the open center 17 of the head 16 is a mixing tube 27, which is formed with a flared lower end 28 and a perforated upper end 29, the latter being covered through the medium of a flame spreader 30, while below the flared end 28 of the mixing tube 27 is a gas nozzle 31 having an inlet tube 32 which is tapped into a valve casing 33, the valves of which are operated by means of valve rods 34 and 35, respectively, which extend downwardly through the base 10, and between these valves within the casing 33 and tapped within the latter is a vertical delivery pipe 36 which is tapped within a depending hollow boss 37 formed on the head 16 at the bottom thereof so that gas from the said head will be supplied to the gas nozzle on the opening of the valve next to the same, the rods 34 and 35 being operated in a manner presently described.
- 50 Arranged concentrically about the nozzle 31 is an air inlet ring 38 which is formed with an annular oil receiving groove or channel 39, at the upper edge thereof, to receive oil to be lighted, so as to serve as a torch for pre-heating the head 16 for the vaporizing of the oil therein prior to the lighting of the burner, whereby the oil will be converted into gas to be consumed at the burner.
- 60 Formed on the head 16 at the top thereof and extended about the periphery and beneath the bottom of the same are radial ribs 40 which form a support for the flame spreader 30, which is separate from the mixing tube 27. The ribs 40 also serve to

admit air to the flame spreader 30 and about the mixing tube during the working of the device.

Tapped in the valve casing 33 on the side opposite the nozzle 31 connected therewith is a gas delivery pipe 41 which is provided with an elbow 42 and a short pipe 43, the latter being tapped into a casing 44 constructed correspondingly to the casing 16 and below which is arranged the gas nozzle 45 and torch ring 46, the same being identical in construction to the nozzle 31 and ring 38, the said nozzle 45 being supplied with gas through the inlet pipes 46' and 47, the same being tapped into a union 48 for joining them, the pipe 47 leading from the head 44.

Working within each of the nozzles 31 and 45 is a needle valve operating rod 49 which extends downwardly through a hollow post 50 supporting the said nozzle, and mounted upon the base 10, while below the latter and loosely mounted upon the said rod 49 is a bracket 51 forming a bearing for a worm screw 52, the latter meshing with a worm gear 53 fixed to the shaft 49, the worm screw 52 being connected with the part 54 of an extensible operating rod 55, another part of which carries a hand wheel 56 so that it can be manually turned for working the needle valve rod 49. The bracket 51 permits the shifting of the rod 55 about the rod 49 so that it can be conveniently positioned for manipulation by the user of the device, because on the application of the device as shown in Fig. 1, the rod 55 is arranged in one position, while on the application of the device in the stove shown in Fig. 3 the rod 55 will have to be positioned at a different angle from the position thereof as shown in Fig. 1 of the drawings.

The valve rod 35 controls the valve within the casing 33 to regulate the supply of gas through the pipe 41 to the nozzle 45, as will be apparent, and this valve rod 35, together with the valve rod 34, is operated in a manner similar to the rod 49 controlling the needle valve of the nozzles 31 and 45, respectively.

In Fig. 3 there is shown a slight modification in the application of the device, wherein B designates the fire pot of an ordinary coal stove, in which is mounted the base 10 of the device, the latter, in this instance, being constructed identically as hereinbefore described.

From the foregoing it is thought that the construction and manner of operation of the device will be clearly understood, and therefore a more extended explanation has been omitted.

What is claimed is:—

1. In a burner, a casing forming a vaporizing chamber, a column depending from said casing, means for supplying oil to said

column, a mixing tube arranged centrally of the said casing, a discharge nozzle below said tube and having communication with said chamber, means for forming a torch 5 concentrically about the discharge nozzle, baffle plates arranged within the said chamber, and baffle plates arranged within the column.

2. In a burner, a casing forming a vaporizing chamber, a column depending from said casing, means for supplying oil to said column, a mixing tube arranged centrally of the said casing, a discharge nozzle below said tube and having communication with said 10 chamber, means for forming a torch concentrically about the discharge nozzle, baffle plates arranged within the said chamber, baffle plates arranged within the column, and means for regulating the discharge of 15 fluid from the said nozzle.

3. In a burner, a casing forming a vaporizing chamber, a column depending from said casing, means for supplying oil to said column, a mixing tube arranged centrally of 25 the said casing, a discharge nozzle below said tube and having communication with said chamber, means for forming a torch concentrically about the discharge nozzle, baffle plates arranged within the said chamber, baffle plates arranged within the column, 30 means for regulating the discharge of fluid from the said nozzle, and means for regulating the delivery of fluid from the chamber to the said nozzle.

35 4. In a burner, a casing forming a vaporizing chamber, a column depending from said casing, means for supplying oil to said column, a mixing tube arranged centrally of the said casing, a discharge nozzle 40 below said tube and having communication with said chamber, means for forming a torch concentrically about the discharge nozzle, baffle plates arranged within the said chamber, baffle plates arranged within the 45 column, means for regulating the discharge of fluid from the said nozzle, means for regulating the delivery of fluid from the chamber to the said nozzle, and a support for the nozzle and casing.

50 5. In a burner, a casing forming a vaporizing chamber, a column depending from said casing, means for supplying oil to said column, a mixing tube arranged centrally of the said casing, a discharge nozzle below 55 said tube and having communication with said chamber, means for forming a torch concentrically about the discharge nozzle, baffle plates arranged within the said chamber, baffle plates arranged within the column,

means for regulating the discharge of fluid 60 from the said nozzle, and adjustable means for regulating the delivery of fluid from the chamber to the said nozzle.

6. In a burner, a casing forming a vaporizing chamber, a column depending from the 65 said casing, means for supplying oil to said column, a mixing tube arranged centrally of the said casing, a discharge nozzle below said tube and having communication with said chamber, means for forming a torch 70 concentrically about the discharge nozzle, baffle plates arranged within the said chamber, baffle plates arranged within the column, adjustable means for regulating the discharge of fluid from the said nozzle, and adjustable means for regulating the delivery of fluid from the chamber to the said nozzle.

7. In a burner, a vaporizer, a mixing tube arranged centrally of said vaporizer, a flame spreader above the mixing tube and supported by the vaporizer, means for discharging fuel into the mixing tube and having communication with the vaporizer, baffle plates arranged within the vaporizer radially with respect to the mixing tube, and a preheating 85 column depending from the vaporizer and having baffle plates arranged therein.

8. In a burner, a vaporizer, a mixing tube arranged centrally of said vaporizer, a flame spreader above the mixing tube and supported by the vaporizer, means for discharging fuel into the mixing tube and having communication with the vaporizer, baffle plates arranged within the vaporizer radially with respect to the mixing tube, a preheating 90 column depending from the vaporizer and having baffle plates arranged therein, and means for supplying oil to the column.

9. In a burner, a vaporizer, a mixing tube arranged centrally of said vaporizer, a flame spreader above the mixing tube and supported by the vaporizer, means for discharging fuel into the mixing tube and having communication with the vaporizer, baffle plates arranged within the vaporizer radially 100 with respect to the mixing tube, a preheating column depending from the vaporizer and having baffle plates arranged therein, 105 means for supplying oil to the column, and means concentrically about the fuel discharge means to effect a torch.

In testimony whereof I affix my signature in presence of two witnesses.

THOMAS J. McADAMS.
